UNITED STATES PATENT OFFICE.

WILLIAM A. BLOMGREN, OF CHICAGO, ILLINOIS.

PHOTO-ENGRAVING APPARATUS.

SPECIFICATION forming part of Letters Patent No. 432,783, dated July 22, 1890.

Application filed March 1, 1890. Serial No. 342,221. (No model.)

To all whom it may concern:

Be it known that I, WILLIAM A. BLOMGREN, a citizen of the United States, residing at Chicago, in the county of Cook and State of Illinois, have invented certain new and useful Improvements in Photo-Engraving Apparatus, which are fully set forth in the following specification, reference being had to the accompanying drawings, forming a part hereof, and in which—

Figure 1 shows the front of the clock mechanism, dial, and hands and partially the means of making electrical connection, as shown, behind the broken-away portion of the dial, and hands set ready for work. Fig. 2 is an end view of the same device. Fig. 3 shows the dial of Fig. 1 on its reverse or interior side. Fig. 4 shows the clock mechanism of my device, as seen in front elevation, with the front or parts shown in Figs. 1 and 3 removed, so as to expose the clock mechanism, a part of which (and which performs no special function here) being indicated in broken lines only, the auxiliary or secondary clock mechanism being shown in operative contact with the main clock mechanism and ready for work. Fig. 5 shows Fig. 1 with its front replaced and cut by a horizontal plane above the shaft which carries the clock-hands, so as to show the mechanism below such plane. Fig. 6 shows Fig. 4 with all its parts replaced, as seen when cut by a vertical plane passing between the shaft of the escapement-wheel and the shaft carrying the hands, so as to show the mechanism between said plane and the weight in the clock, as seen from the winding-mechanism side. Fig. 7 shows the lower end of the inner side of the side of the clock which has the winding and starting mechanism, so as to show the starting mechanism in side view. Fig. 8 shows in plan view the lever which brings the auxiliary or secondary clock mechanism in contact with the regular clock mechanism, and also shows its fulcrum. Fig. 9 shows in side elevation my clock, battery, bell, and photographer's camera, all connected and set ready for action, the camera being partly broken away on the side, so as to show its interior mechanism.

Like letters refer to like parts.

The object of my invention is to produce a

mechanism which, by means of a clock and an auxiliary clock mechanism connected therewith, an electric circuit, and bell, I shall be enabled to time with accuracy the length of exposure required for zinc-etching prints, photographing, and, in short, wherever certain definite periods of time are required and whereby the undivided attention of an operator shall not be required, and thus enable him to at the same time attend to one or more additional instruments or to other duties, and to attain said desirable end I construct my new and improved mechanism in substantially the following manner, namely:

I take any common clock-work a and connect with it an auxiliary or secondary clock-work A. As here shown, a part of the latter is carried on a lever a' , which is fulcrumed at a^2 . The mechanism carried by said lever consists of a sector a^3 , carrying on its shaft an arm a^4 , to which is attached a connecting-rod a^5 , which connects with a geared sector a^6 , journaled to the frame of the clock-work a . At the outer end of the lever a' is a spring a^7 , of which the upper end is connected to an adjusting-screw in the clock-case, by means of which the tension of said spring may be regulated. An intermediate wheel a^8 connects the clock-works a and A. Said wheel a^8 is placed at any suitable place in contact with any one of the train of wheels of the clock a , which will give the proper speed to the train of wheels of the clock mechanism A to give the required motion to the hand a^9 . A lever with pawl-and-ratchet mechanism, as shown in Figs. 2, 4, and 5, may be used to wind the clock a , or in lieu thereof any other suitable and well-known mechanism may be employed.

There is a spring c on the shaft of the geared segment a^6 , which counteracts the motion of said segment and tends to prevent lost motion. On the shaft a^9 , which carries the hands a^7 a^{10} , is wound a cord c' , attached to a weight run over a pulley, as shown, which tends to return the said hands to the starting-point and also tends to prevent lost motion. The hands a^7 a^{10} are set by means of an adjusting-screw e , which checks the motion of a lug e' , forming a part of the sector a^6 .

On the short end of the lever a' is attached a catch b , which is held by a hook b' , forming

a part of the oscillating lever b^2 , fulcrumed or pivoted at b^3 . Said lever, with its hook, is drawn toward the lever a' by means of the spring b^4 . On the inner side of the dial is a 5 spring b^6 , which carries a push button or stud b^5 , the inner end of which is in close proximity to a projection of the lever b^2 . The operation of the entire mechanism will be most 10 easily understood by first describing the operation of the above-described parts, which will now be done.

The clock mechanisms a and A are now shown in operative contact. Such contact is made by the force of the spring a^9 , which 15 forces the parts $a^3 a^x$ into frictional contact, preferably grooved or rubber-faced peripheral surfaces being given to said gearing, because there is less lost motion. The said parts then move, respectively, as shown by 20 the arrows. When it is desired to stop the motion of the mechanism A , (the mechanism a is to be in constant motion,) the outer end of the lever a is lifted up. This stretches the spring a^9 , separates the parts $a^3 a^x$, and causes 25 the hook b' to snap under the catch b on lever b^2 . When it is desired to start the mechanism A , the stud b^5 is pushed until it pushes back the lever b^2 , so as to disengage the hook and catch b' b , after which the spring a^9 will raise 30 the inner or long end of the lever and bring the two mechanisms into the position now shown. To the clock-case are attached binding-posts carrying insulated wires d and d' from the two sides of a galvanic battery, respectively, one side d' going to the shaft carrying the hands of the clock a , and the other wire d going down to the lower left-hand corner of the clock-case, where it rests on the surface of the edge of the side of the clock- 35 case and there is brought in contact with another wire placed on the inner surface of the front of the clock, as shown in Fig. 3, which at their junction are uncovered, so as to make the current continuous, as one wire, and on the 40 inside of said front the said wire is changed into the form of a flat brass spring d^2 , which is in frictional contact with the brass wheel d^3 , mounted on an insulating-hub h , which passes through the clock-face and over the 45 shaft carrying the hands of the clock a . On said wheel d^3 is a hand d^4 , to which is attached a spring d^5 , which is in contact with said hand and extends beyond it, and at its outer end carries a semi-cylindrical end d^6 , and to 50 the outer end of said insulating-hub is attached a hand d^7 , which is parallel to the inner hand d^4 , and firmly attached, so as to always point with it in the same direction. The hand a^7 and the pinion on the shaft a^9 , 55 actuated by the sector a^6 , are also firmly attached and move together, and on the outer end of the shaft a^9 is attached a hand a^{10} , which is parallel and also moves with the interior hand a^7 and indicates the time on the 60 clock-dial. The hand a^7 also has a semi-cylindrical projection at its outer end, which sweeps in the same circle as does the part d^6 , 65

said parts facing each other and are arranged to come in contact when their said hands are parallel, and thus by the contact of said points 7c complete the electric circuit for a short time, the said spring d^5 yielding as the said cylindrical surfaces slip over each other, causing a bell B to ring.

The operation of the last-described mechanism is substantially as follows, namely: Suppose that it is desired to expose a plate in a camera fifteen minutes, the hand d^7 is turned to indicate that time on the dial, and the hands $a^7 a^{10}$ being adjusted to the starting point, the outer hand striking against the stop d^8 , the push-button b^5 is then pressed until the parts $a A$ snap into contact as the clock goes on. The hand a^7 will move on until it comes in contact with the part d^6 , when it 85 will complete the electric circuit and cause the bell B to ring, thereby informing the operator that the required time has passed.

A photographer's camera may also form an additional element in the electric circuit and 90 be used in connection with the clock and bell, as shown in Fig. 9, the electric circuit in this case closing the shutter of the camera and at the same time ringing the bell. The shutter f is hinged at f' and has a spur f^2 , 95 placed and projecting from the shutter about as shown, and above said parts is placed an electro-magnet g , the armature g' of which, playing between vertical guides, has a catch g^2 , which holds the spur f^2 , as shown, when 100 the shutter f is open. When the circuit is closed, the armature is attracted by the magnet, and thus raises the catch g^2 above the spur f^2 , thus relieving the said parts from each other and allowing the shutter to fall. 105 It should also be observed that the shaft a^9 is not geared with the clock-work a , but that it is actuated by the auxiliary clock mechanism A only, as shown.

When thought desirable, the clock-dial may 110 be made of glass and the figures and divisions on it may be engraved in the glass, then only one hand for each set, instead of two, will give the same result, and only a button on the face of the dial, or any other means on 115 any other part of the mechanism, would be necessary to set the hand d^4 , and the hand d^7 could then be seen at any of its positions both before and after it had made the electrical contact.

What I claim is—

1. In a time apparatus for photo-engraving, a continuously-acting clock-movement actuating a secondary clock-movement, in combination with a dial provided with two 125 independent sets of hands, each set of hands consisting of one or more members, whereof one of each of said set of hands is provided with means to make an electric circuit when said sets of hands pass over each other, substantially as specified.

2. In a time apparatus for photo-engraving, a continuously-acting clock-movement, in combination with a secondary clock-move-

ment, and a dial provided with two independent sets of hands, a camera-shutter and a bell operated by electro-magnets, and an electric circuit adapted to be closed by said hands and operate said shutter and bell, substantially as specified.

5 3. In a time apparatus for photo-engraving, a continuously-acting clock-movement, and a secondary clock-movement adapted to be engaged and disengaged from said con-

tinuously-acting clock-movement, in combination with a dial provided with two independent sets of hands, and means whereby said hands may make an electric circuit, and thereby operate electro-magnetic mechanism, 15 substantially as specified.
